(57) **CLAIM**

The ornamental design for a flow shaper for sprinkler assembly, as shown and described.

DESCRIPTION

FIG. 1 is a perspective view of a flow shaper for sprinkler assembly;

FIG. 2 is a top plan view thereof;

FIG. 3 is a rear view thereof;

FIG. 4 is a left side view thereof;

FIG. 5 is a front side view thereof; and,

FIG. 6 is a left side view thereof.

The lines shown in phantom are for illustrative purposes only and do not form part of the invention.
